ATTORNEY

UNITED STATES PATENT OFFICE.

ISAAC N. HENNESS, OF ILWACO, WASHINGTON.

ICE-VEHICLE.

SPECIFICATION forming part of Letters Patent No. 734,552, dated July 28, 1903.

Application filed March 1, 1902. Serial No. 96,315. (No model.)

To all whom it may concern:

Be it known that I, ISAAC N. HENNESS, a citizen of the United States, residing at Ilwaco, in the county of Pacific and State of Washington, have invented certain new and useful Improvements in Ice-Vehicles, of which the following is a specification, reference being had therein to the accompanying drawings.

This invention relates to improvements in vehicles designed to propel themselves and, if desired, of hauling other vehicles over the ice or snow.

The object of the invention is to provide a vehicle capable of traversing rough ice, deep snow, and slush, which I attain by the construction and arrangement of parts hereinafter described, and illustrated in the accompanying drawings, wherein—

Figure 1 is a plan view of a vehicle embodying my improvements. Fig. 2 is a central longitudinal vertical section of the same. Figs. 3 and 4 are respectively enlarged perspective views of a propeller-shoe and the steering-rudder.

Referring to the said drawings, the vehicle consists of a water-tight body comprised of side plates *a* and a bottom plate *b*, bent upwardly to form ends *b'*; suitable framing to provide structural strength to the same, and longitudinal runners *c*, extending throughout the body length and to some distance rearwardly thereof.

d represents a steam-boiler and its attachments, and *e* an engine.

To the after end of the vehicle-body is journaled in boxes *f* a multiple crank-shaft *g*, which is rotated by a link belt *h*, passing around sprocket-wheels *i i'* upon the said crank-shaft and the engine-shaft, respectively. To the several crank-pins of said shaft are pivotally connected push-bars *k*, having shoes *l*, which engage with the ice or other supporting-surface. The said shoes *l* (see Fig. 3) are each formed of a plate curved near one end to form a ball *m*, upon which to slide in their forward travel, a flange *m'* at the other end, and a hollow or cavity *m''* therebetween.

Projecting forward of the vehicle-body is an extension-piece *o*, folded back at its outer end to provide double bearings *o'* for the post *p* of rudder *p'*, which is vertically movable

therein to compensate for the irregularities of the surface being traveled over. In order to exert a greater downward force or more friction upon the ground than that due simply from the weight of the rudder and its attachments, I fork the tiller end *q* so as to straddle the said post and pivotally connect them by a pin *q'*, eccentric of the perimeter of the said forked end, and thus provide a fulcrum against the upper fold *o''* of the piece *o* by raising the handle end of the tiller after the rudder has been swung around to the proper steering-angle. Wings *p''*, integral with the rudder, are intended as supports for the rudder when in slush or soft snow.

To remove snow-drifts encountered in the path of the vehicle or in opening new roads, I contemplate using, in combination with the vehicle, a snow-shoveler which consists of a double-bladed shovel *2*, mounted upon the extremity of a shaft *3 3*, which is rotated from the engine by link belt *4*; sprocket-wheels *5 5'*, and bevel-pinion *6* and gear-wheels *7 8*. The shaft *9* of sprocket-wheel *5* and pinion *6* is journaled in fixed boxes *10*. The gear-wheel *7* is mounted upon a vertical shaft *12*, journaled in bracket-box *13*, and seated thereon, so as to seat loosely about shaft *12*, is the hub of a swiveling frame *14*, carrying the journal-boxes *14'* of shaft *3*. Positioned between the last-named boxes and splined to shaft *3* is a sleeve *15*, upon which are fixed the bevel gear-wheels *8*, adapted to mesh with bevel-wheel *7* for rotating the said shaft in either direction. This is accomplished by means of a lever *11*, fulcrumed at *11'* to the swiveling frame and engaging with horns *11''* of the said sleeve, whereby the latter may be shifted so as to put either of the said wheels *8* into or out of engagement. The shaft parts *3 3* are connected by a universal joint *20*, so as to deflect the same out of a right line in either a vertical or horizontal direction, the outer part *3* being controlled by a lever *16*, fulcrumed at *17* to the frame *14*, which is intermediate of the handle end *16'* and its connection *16''* with a sleeve-bearing *18*, located in proximity with the rotatable shovel.

By means of the swivel mounting of frame *14* the shaft *3* may be directed toward any angle with the axis of the vehicle, and by means of the said universal joint on the

shaft the shaft may be swung vertically or horizontally. Consequently the shoveling or, more correctly, scraping may be done anywhere within reach of the device with ease and despatch. The fact that the direction of rotation of the shovel may be reversed is of importance, inasmuch as the material to be handled can be moved from either side and in either transverse direction.

10 The operation of the vehicle-propelling device is extremely simple and is adapted to accomplish the purpose for which designed—namely, the rapid propulsion of the vehicle over rough or humpbacked ice or snow surfaces—an important element to its successful operation being the foot-piece or shoe 7, whereby the vehicle may be propelled upon either hard ice or soft snow or slush. Also, in the latter the flat toboggan-like bottom of 15 the vehicle-body supports the same against immersion therein.

Having thus described my invention, what I claim as new, and desire to secure by Letters Patent, is—

20 25 1. In an ice-vehicle, the combination with the body having a waterproof body portion, propelling push-bars, and a steering device;

of means to clear a path of snow or the like in advance of the vehicle, such means comprising revoluble blades fixedly mounted upon a swinging shaft projecting forward of the vehicle-body, devices whereby the said shaft can be rotated in opposite directions, substantially as described.

2. As a means of clearing the path in advance of an ice-vehicle, the bevel-pinion 6, shaft 9, bevel-wheel 7 mounted on a vertical shaft 12, a frame 14 swiveled on last-named shaft, another shaft 3 journaled in frame 14, a sleeve splined to shaft 3 and having a bevel gear-wheel fixedly mounted to its opposite ends, means to shift the said sleeve lengthwise upon shaft 3, a universal joint in shaft 3, a blade or blades 2 mounted upon the outer extremity of shaft 3, and an outer sleeve-bearing 18 and lever 16, arranged and operating as herein shown and described.

In testimony whereof I affix my signature in presence of two witnesses.

ISAAC N. HENNESS.
